UNITED STATES PATENT OFFICE.

FRED M. YOUNG, OF RACINE, WISCONSIN, ASSIGNOR TO RACINE RADIATOR COMPANY, OF RACINE, WISCONSIN, A CORPORATION OF WISCONSIN.

SECTIONAL RADIATOR FOR MOTOR VEHICLES.

Application filed March 16, 1925. Serial No. 15,882.

This invention relates mainly to internal combustion engine radiators, and more especially to large capacity sectional radiators adapted for portable power plant units and 5 having top and bottom tanks with interchangeable radiating means interposed.

The main objects of the invention are to provide a simplified and more durable form of radiator construction adapted for ready

- 10 manufacture and interchangeability of parts for renewals and repairs; to provide an improved form of construction for the top and bottom end connections of the radiator part, means or sections; to minimize the
- 15 amount of coring necessary for molding the parts; to provide a better form of individual section headers, adapted for exterior application of the fasteners; to provide an improved form of top and bottom tanks; to
- 20 provide such headers and tank connections therefor adapted to accommodate and assure equalization of water distribution throughout all of the passageways in each section; and to provide for loose fitting fasteners which may be readily set tightly in clamping relation to hold the sections demountably; and to so construct the section headers and seats therefor on the tanks that tight connections may be attained by a
- 25 single manually releasable fastener at each joint.

An illustrative embodiment of this invention is shown by the accompanying drawings, in which—

- 30 Fig. 1 is mainly a front elevation of the upper part of a radiator with the right hand unit in vertical cross section, as at the line 1—1 on Fig. 2.

Fig. 2 shows mainly a vertical cross section on the line 2—2 of Fig. 1, the upper part of the view being in side elevation.

- 35 Fig. 3 is mainly a cross section through the bottom part of the radiator, on the line 3—3 of Fig. 4.

Fig. 4 is a fragmentary front view of the lower right hand corner of the radiator represented in Fig. 1, with the right hand unit shown in vertical cross section, corresponding with the upper end thereof as viewed in 45 Fig. 1.

- 50 Fig. 5 is mainly a perspective view of the upper header or cap member of one of the units shown in Fig. 1, part of the wall being broken away to more clearly show the details of form and character of construction.

Fig. 6 is an enlarged detail of Fig. 2 and shows especially one of the water passageways and the gasket interposed between the tank and the header.

Fig. 7 is similarly an enlarged detail of Fig. 3 and shows the loose fit of the through-bolt in the cored hole of the tank.

Fig. 8 is such a section on the line 8—8 of Fig. 3 and well shows the tank bolt hole.

In the construction shown in the drawings the radiator 1 comprises a plurality of heat radiating sections 2 in combination with a top tank 3, a bottom tank 4 and a pair of upright end frame connectors 1'. These tanks and sections are so formed with 50 mutually overlapping flange parts herein-after described that each end joint may be and is secured by a single loose fitting tension fastening 5, and the abutting tank and section-end parts or headers are each composed solely of an integral casting.

Referring now to the construction of the radiator sections or units 2, each comprises a central main body part or core 6 of vertically apertured cellular structure in combination with a pair of terminal parts or headers 7, one at each end, with which the vertical water passageways all communicate. The headers 7 are substantially alike and are secured permanently and substantially 55 integrally to the core 6 at their edges 7', as by welding or equivalent means. These sections are symmetrically formed and may be used either end up.

Each header 7 is formed substantially as 60 shown in Fig. 5, and is preferably made as a casting either from brass or malleable iron. They may also be stamped and formed into shape from sheet metal. Said Fig. 5 shows that position of the header 65 which it assumes when disposed at the top of the core 6. It is formed as a closed box-like member open at 7' on its under side to receive the core 6, which is welded to its downward edges as at 7''. The upper rear 100 corner is recessed at 8 to receive a corresponding flange part or leg 9 of the tank 3. The upper side of the header is indented transversely at 10 from front to back to provide a trough-like notch or aperture for the 105 fastening bolt 5 which fits loosely therein. A pair of port apertures 11 are provided in the upright wall 12 of recess 8, one on each side of the depression 10 to register with corresponding port apertures 13 in the inner 110

wall 9" of the depending leg 9 of tank 3 for the flow of water, as required for circulation in the radiator.

The cores 6 may be constructed in any desired manner consistent with efficiency, substantially as usual in the art. The ends of said cores fit flush with and against the open sides of the headers 7 respectively, where they are welded together around the edges. Gaskets 14 are provided for each of the fluid tight joints corresponding with the ports 11 and 13.

The bolts 5 fit loosely in cored holes 9" in the leg 9, and likewise they fit loosely in the troughs 10 entirely out of contact with moisture and consequently free from the tendency to rust. No drilling or tapping of holes is required either in the tanks or in the headers. The bolts 5 are simply held in tension by the nuts 5' and serve effectively to maintain a tight joint, which is easily accessible by removal of said nuts.

Assuming that the radiator is assembled complete, the method of removing a section 25 2 is to remove the corresponding pair of nuts 5' on the front side at the top and bottom and then pull the section horizontally forward and off. It may be put on by a simple reverse method, which, however, must include holding the loosely disposed bolts 5 positively in place against backing out, toward the right as viewed in Figs. 2 and 3, unless the gaskets 14 bind snugly enough about the bolts to hold them in place independently of other means.

It should be noted that each of the header castings at the upper and lower ends of the core sections is of uniform depth across the entire width of the core, thus giving uniform distribution for steam and water through to all of the water passages in each core section. Moreover, it is connected to the core tanks by a single standard bolt which passes through both the cored hole 40 45 in the tank and the groove in the section header. The cored hole for the bolt is sufficiently large to allow assembling these radiator sections even if there is a small variation in the length of same or if the castings vary in depth. Also, if in assembling the junction boxes or section-headers on the upper and lower ends of the cores, any header box is not set at exactly right

angles in either direction, still there is sufficient clearance in the cored hole for this 55 bolt because it is a center bolt to permit of these variations, instead of a pair of bolts one on each side.

From a practical economic standpoint in assembling this radiator, there is a very 60 material reduction of cost because of these features. Furthermore, in removing the section, there are only two rough bolts to disconnect instead of four machined cap screws. A rough bolt can be readily obtained as compared with specially machined screws, and the fluid passageways which are cored in the back portion of these headers are so placed on either side of the bolt housing as to give substantially uniform 70 distribution to each core section, and these holes are of such form and area as to accommodate some variance in horizontal axial registry with the holes in the upper and lower tank castings and still provide sufficient open area for the maximum volume of water or steam necessary.

Instead of there being an individual opening connected with the tank, there is along the back of each header practically a continuous passage for taking the water into and through the openings in the header boxes.

Although but one specific embodiment of this invention is herein shown and described, it is to be understood that some of the details of the construction shown may be altered or omitted without departing from the spirit of this invention as defined by the following claim.

I claim:

In a radiator, upper and lower tanks rigidly connected one above the other, a plurality of core sections each having upper and lower headers overlapping vertical faces of said tanks, each of said upper and lower headers having a deep notch in its top and bottom end respectively to accommodate bolts for securing such headers to the adjacent tanks, and bolts in said notches arranged to secure each core section independently of the others.

Signed at Chicago this 12th day of March, 1925.

FRED M. YOUNG.
